UNITED STATES PATENT OFFICE.

HERMAN KRAUSE, OF LINCOLN, NEBRASKA.

DESIGN FOR A PENNANT.

56,700.

Specification for Design.

Patented Nov. 30, 1920.

Application filed September 2, 1919. Serial No. 321,282. Term of patent 3½ years.

To all whom it may concern:

Be it known that I, HERMAN KRAUSE, a citizen of the United States, residing at Lincoln, in the county of Lancaster and State of Nebraska, have invented a new, original, and ornamental Design for Pennants, of which the following is a specification, reference being had to the accompany-

ing drawing, forming part thereof, the drawing being ruled to indicate colors.

The figure is a side elevation of a pennant, showing my new design.

I claim:

The ornamental design for a pennant, as shown.

HERMAN KRAUSE.
